PROCESS FOR THE CONVERSION OF
PETROLEUM OIL

Carbon P. Dubbs, Wilmette, Ill., assignor, by
mesne assignments, to Universal Oil Products
Company, Chicago, Ill., a corporation of Dela-
ware

Continuation of application Serial No. 587,883,
September 13, 1922. This application May 14,
1930, Serial No. 452,199½. Renewed June 27,
1934

5 Claims. (Cl. 196—48)

This invention relates to a process and apparatus for the conversion of petroleum oils and relates more particularly to the conversion of oils under substantial pressure, to change the oils 5 from relatively high boiling point oils to low boiling point oils similar to distillates having the characteristics of gasoline and the like.

This application is a continuation of my application filed September 13, 1922, Serial No. 10 587,883.

Among the objects of the invention are to provide a process in which utilization of the heat for pre-heating and the dephlegmation of the oil vapors in the refluxing zone combine to form 15 a more efficient process in operation, and give more satisfactory results in the products obtained.

The single figure is a diagrammatic side elevational view of the apparatus with parts broken away in order to disclose more clearly the features of the process.

Referring to the drawing, the oil stock to be treated is introduced from any convenient extraneous source through the line 1, and is charged by means of the pump 2 through the line 3 controlled by the valve 4 and may be directed through the pre-heating coil 5 and thence through lines 6 and 7 to the heating coils 8 by proper manipulation of the valves 4, 45, 43 and 44, or by closing the valve 4 and opening the valve 9 into lines 10 the raw oil charge may be introduced and circulated through the coil 11. This pre-heating coil is situated just above that part of the dephlegmator into which the vapors are introduced, and terminates in a perforated circular 35 pipe or hose 12 discharging the preheated oil into vertically arranged perforated pans 13 through which the oil percolates in a broken up condition, passing off through the bottom of the dephlegmator 14, through the dephlegmator leg 15. The 40 draw-off line 1, controlled by valve 16 directs the oil from the bottom of the dephlegmator leg 15 to the heating coils 8.

The heating coils are mounted in a side fired furnace 17 and while circulating through the 45 coils 8, the oil is raised to a conversion temperature and passes from the heating coils through the transfer line 18 to the expansion chamber 19. The expansion chamber has residuum draw-off lines 20 and 21 controlled by valves 22 and 23. In this expansion chamber, the oil is permitted to collect in a substantial body and during a digestion and vaporization period the oil vapors are evolved which pass off through the 50 line 24 controlled by the valve 25 to the dephleg-

5 mator 14, and where as explained, they are introduced just below the pre-heating coil 11.

The oil vapors on their introduction to the dephlegmator are first subjected to the dephlegmating action of the pre-heating coil 11 which 5 is filled with the cool charging stock, and as they rise into the upper portion of the dephlegmator they come in contact with the coil 5 and finally with the returned distillate which is recirculated from the receiver 26 through the lines 27 and 28 10 into the top of the dephlegmator through the coil 29 and spray pipe 30. The oil vapors that remain uncondensed, arriving at the top of the dephlegmator pass off through the vapor line 31 controlled by valve 32 to a water condensing coil 33 15 mounted in condenser box 34. The discharge end of the condenser coil is connected by pipe 35 regulated by valve 36 to the receiving tank 26 which is equipped with a pressure relief valve 37, liquid draw-off valve 38 and liquid level 20 gauge 39.

The distillate as explained, may be returned through the line 27 and charged by means of the pump 40 through line 28 controlled by valve 41 to the top of the dephlegmator where it may be 25 passed as a cooling medium through the valve 45 into the coil 5 and thence through the line 42 controlled by valve 43 to any convenient storage tank, or returned by closing the valve 43 and opening the valve 44 to the line 7 where it is 30 recirculated with a charging stock to the heating coil.

An alternate method of returning the distillate is to close the valve 45 and open the valve 41 thereby introducing the distillate to the coil 29 35 and discharging it from the perforated pipe 30 into the upper pan of the dephlegmator. These alternative methods of controlling the temperatures in the dephlegmator or refluxing tower furnish a very accurate control of the temperature 40 therein whereby the reflux condensate separated from the vapors may be accurately controlled and the character of the distillate passing over to the receiver, regulated to predetermined ranges.

The introduction of the raw oil below the vapor pipe in the refluxing column prevents the shocking of the light ends contained in the charging stock which usually results in their being carried over with the heated oil vapors to the condenser 50 and receiver. By utilizing the apparatus explained, the charging stock is contained in a closed coil during its circulation through the heated oil vapors whereby the pre-heating action is not attended by intimate contact between 55

the highly heated vapors and the volatile products of the charging stock, and it is not until the charging stock has reached a level below that portion of the dephlegmator where the oil vapors 5 are introduced that it is discharged into the dephlegmator proper.

Below this point the temperatures are less, due to the returned distillate and separated condensate gravitating from the upper portions of 10 the dephlegmator so the oil discharged in this manner will get the pre-heating effect and at the same time will not be relieved of its lighter ends which are objectionable when carried over with the vapors to be combined with the distillate 15 in the receiver.

The character of the apparatus may be varied without departing from the spirit of the invention.

Having thus described my invention, what I 20 claim is:—

1. A continuous process for converting petroleum oils, consisting in raising the oil to a cracking temperature in an elongated passageway, passing the highly heated oil to a vapor chamber, 25 vaporizing the oil in said vapor chamber while maintaining a substantial body of oil therein, dephlegmating the evolved vapors, and subjecting them to a final condensing action, returning distillate from the final condensing stage to the 30 dephlegmator to pass through a coil therein as a refluxing medium, discharging said distillate from the coil into the dephlegmator at a point near which the oil vapors are discharged from the dephlegmator, introducing raw oil to the dephlegmator to pass through a coil above the point at 35 which the vapors are introduced to the dephlegmator, and in discharging the raw oil from said coil into the dephlegmator at a point below the point of introduction of said vapors, and in continuously supplying raw oil and reflux condensate 40 to the elongated passageway for treatment.

2. A conversion process which comprises subjecting hydrocarbon oil to cracking conditions of temperature and pressure in a heating coil, separating the heated oil into vapors and residue 45 in a separating chamber, introducing the vapors to a fractionating column at an intermediate point in the height of the column substantially above the bottom thereof, introducing preheated charging oil for the process to the column below said point but a substantial distance above the bottom of the column and passing it downwardly to the bottom of the column, whereby to release 50 lighter fractions of the charging oil out of contact

with the vapors being introduced at said intermediate point, fractionating the vapors in the upper portion of the column above said point to condense heavier fractions thereof, removing the fractionated vapors from the top of the column and finally condensing the same, introducing a portion of the resultant final condensate into contact with the vapors undergoing fractionation in the upper portion of the column as a refluxing medium for the vapors, and supplying admixed reflux condensate and unvaporized charging oil from the bottom of the column to the heating coil. 5

3. A conversion process which comprises subjecting hydrocarbon oil to cracking conditions of temperature and pressure in a heating coil, separating the heated oil into vapors and residue in a separating chamber, introducing the vapors to a fractionating column at an intermediate point in the height of the column substantially above the bottom thereof, passing charging oil for the process in indirect heat exchange with the vapors in the column above said point, then introducing the thus preheated charging oil to the column below said point but a substantial distance above the bottom of the column and passing it downwardly to the bottom of the column, whereby to release lighter fractions of the charging oil out of contact with the vapors being introduced at said intermediate point, fractionating the vapors in the upper portion of the column above said point to condense heavier fractions thereof, removing the fractionated vapors from the top of the column and finally condensing the same, introducing a portion of the resultant final condensate into contact with the vapors undergoing fractionation in the upper portion of the column as a refluxing medium for the vapors, and supplying admixed reflux condensate and unvaporized charging oil from the bottom of the column to the heating coil. 10 15 20 25 30 35 40 45 50

4. The process as defined in claim 2 further characterized in that said portion of the final condensate, prior to its introduction into contact with the vapors in the upper portion of the column, is passed in indirect heat exchange with the vapors being removed from the top of the column. 45

5. The process as defined in claim 3 further characterized in that said portion of the final condensate, prior to its introduction into contact with the vapors in the upper portion of the column, is passed in indirect heat exchange with the vapors being removed from the top of the column. 50
